UNITED STATES PATENT OFFICE

170,121

CHAIR

Harlan C. Jackson, New York, N. Y.

Application February 27, 1953, Serial No. 23,823

Term of patent 7 years

(Cl. D15—8)

To all whom it may concern:

Be it known that I, Harlan C. Jackson, a citizen of the United States and a resident of the city, county, and State of New York, have invented a new, original, and ornamental Design for a Chair, of which the following is a specification, reference being had to the accompanying drawings forming a part hereof.

I claim:

The ornamental design for a chair, substantially as shown.

HARLAN C. JACKSON.
